UNITED STATES PATENT OFFICE.

FREDERICK R. CORNWALL, OF ST. LOUIS, MISSOURI, ASSIGNOR TO CHICAGO RAILWAY EQUIPMENT COMPANY, OF CHICAGO, ILLINOIS, A CORPORATION OF ILLINOIS.

SIDE BEARING FOR RAILWAY-CARS.

SPECIFICATION forming part of Letters Patent No. 694,461, dated March 4, 1902.

Application filed November 19, 1901. Serial No. 82,900. (No model.)

To all whom it may concern:

Be it known that I, FREDERICK R. CORNWALL, a citizen of the United States, residing in the city of St. Louis, State of Missouri, have 5 invented a certain new and useful Improvement in Side Bearings for Railway-Cars, of which the following is a full, clear, and exact description, such as will enable others skilled in the art to which it appertains to 10 make and use the same, reference being had to the accompanying drawings, forming part of this specification, in which—

Figure 1 is a top plan view of my improved side bearing. Fig. 2 is an end elevational 15 view, one end being shown in vertical section. Fig. 3 is an end elevational view. Fig. 4 is a vertical cross-sectional view. Fig. 5 is a plan view of a modified form; and Fig. 6 is 20 an elevational view of said modified form, one end thereof being shown in section.

This invention relates to a new and useful improvement in side bearings for railway-cars, the object being to construct a device of the character described in a simple and cheap 25 manner.

Another object is to provide means for restoring the antifriction devices to a normal or central position, said restoring means being contained within the said bearing proper, 30 and another object is to utilize the movement of the antifriction devices in a reverse direction to store power in a restoring medium.

With these objects in view my invention consists in the construction, arrangement, 35 and combination of the several parts, all as will hereinafter be described, and afterward pointed out in the claims.

In the drawings, 1 indicates a casting provided with the usual lugs for attachment to 40 a bolster. This casting is provided with a continuous groove or way 2, one portion of which is open at its top and through which antifriction devices in the form of balls 3 protrude. The bottom of this way is formed by 45 a hard-metal track plate or bar 4. The upper edges of this groove extend inwardly toward each other to confine the antifriction-balls in position. The ends of the way may or may not be inclined, but I have shown them

inclined, said inclined end ways containing 50 balls, preferably of the same size as those on the elevated way, in which are arranged the exposed balls. It will be noted that the balls in the inclined way are partially housed and that the ends of the casting are cut away, as 55 at 6, in order to permit dirt, cinders, water, &c., to escape.

7 indicates what I will term for the sake of distinction the "bottom way," which is preferably larger than the top way, said bottom way being open at its top in order to introduce the antifriction-balls and to drop into position the spring-followers 8 and their interposed spring 9. A cap or cover 10 is arranged to close this way. Instead of having 60 the bottom way larger than the top way said bottom way may be of the same size as the top way; but whether larger or of the same size shoulders 11 must be provided to arrest the outward movement of the spring-followers. These spring-followers (shown in Fig. 2) are in the form of castings with centering-teats for the spring, while in Fig. 6 they are 65 in the form of balls of larger diameter, (indicated at 8^a.)

In operation the device being assembled as shown in the drawings, the side bearing is attached in position on the bolster. The way in which are located the antifriction-balls is preferably curved concentric to the king-pin 80 of the truck. Whenever the bearing-plate on the body-bolster contacts with the antifriction devices in the form of exposed balls, said balls are moved in their way in either direction, as the case may be, forcing the follower in advance of the active ball at the end of the row to move inwardly, compressing the spring and storing up power in said spring to restore the antifriction devices to their normal position 85 immediately upon being relieved from the load. It follows that these antifriction-balls will be responsive to the movement of the bearing on the body-bolster in either direction, that the active spring-follower will be moved in a direction opposite the direction 90 of movement of the burden-carrying balls, that the receding spring-follower will permit 95 the active balls to house themselves in the

spring-housing, and that as soon as the burden-carrying balls are relieved from their load the spring exerts its energy to force the balls around to their normal position, which is determined by the balls contacting with each other or by the spring-followers contacting with their fixed abutments.

I am aware that many minor changes in the construction, arrangement, and combination of the several parts of my device can be made and substituted for those herein shown and described without in the least departing from the nature and principle of my invention.

Having thus described my invention, what I claim, and desire to secure by Letters Patent of the United States, is—

1. In a side bearing for cars, the combination with an antifriction device, and a restoring medium actuated in a direction opposite to the movement of the antifriction device in service; substantially as described.

2. In a side bearing for cars, the combination with an antifriction device, of resilient means for restoring said antifriction device, and means between said antifriction device and said restoring means for reversing the movement of the former to store up power in the latter; substantially as described.

3. In a side bearing for cars, the combination with a series of antifriction devices, of a restoring medium therefor, and means for storing power in said medium in a direction opposite the movement of any of the antifriction devices in service; substantially as described.

4. In a side bearing for cars, the combination with a row of balls, of resilient means for restoring said balls to their normal position, and means operated by the end balls of the row for storing up power in said restoring medium in a direction opposite the movement of the balls of the row in service; substantially as described.

5. In a side bearing for cars, the combination with a row of balls, of a compression-spring for restoring the same to a normal position, the end balls of the row coöperating with said compression-spring; substantially as described.

50 6. In a side bearing for cars, the combination with a row of balls, of spring-followers against which the end balls are seated, and a spring interposed between said followers; substantially as described.

55 7. In a side bearing for cars, the combination with a casting formed with an endless way, of balls in a portion of said way, and a restoring-spring in another portion of said way; substantially as described.

60 8. In a side bearing for cars, the combination with a casting formed with a continuous way, abutments or stops in said way, spring-followers coöperating with said abutments, a spring interposed between said followers, and

a row of balls coöperating with the said spring- 65 followers; substantially as described.

9. In a side bearing for cars, the combination with a casting having a continuous way, of different areas, a row of balls in the way of smaller area, and a restoring-spring for said 70 balls in that portion of the way which is of larger area; substantially as described.

10. In a side bearing for cars, the combination with a casting formed with a top way, a bottom way, and inclined end ways, of balls 75 in said top and inclined ways, and a restoring-spring in the bottom way; substantially as described.

11. In a side bearing for cars, the combination with a casting having an endless way, of 80 a row of exposed balls in a portion of said way, a restoring-spring in another portion of said way, and a housing for said restoring-spring; substantially as described.

12. In a side bearing for cars, the combination with a casting formed with an endless way, said way forming in part a ball-race, and in part a spring-housing, balls in said race, and a spring in said housing; substantially as described. 90

13. In a side bearing for cars, the combination with a casting formed with a continuous way, of balls arranged in a portion of said way, means for confining said balls in position in said way, abutments in said way, spring-followers coöperating with said abutments, a spring interposed between said followers, and a cover-plate for housing in said spring and its followers; substantially as described. 95

14. In a side bearing for cars, the combination with a casting having a continuous way of differential areas, of a row of balls arranged in said way, the end balls of said row being of relatively larger diameter and coöperating with shoulders in the way whereby said balls 105 of larger diameter serve as spring-followers, and an expansion-spring interposed between said balls of larger diameter; substantially as described.

15. In a side bearing for cars, the combination with a casting formed with a continuous way, a track-plate in a portion of said way, a row of balls in said way which is supported in part by said track-plate, said casting having inwardly-extending lips to confine said 115 balls in position, spring-followers coöperating with the balls at the ends of said row, a spring interposed between said followers, and a covering for said spring; substantially as described. 120

In testimony whereof I hereunto affix my signature, in the presence of two witnesses, this 15th day of November, 1901.

FREDERICK R. CORNWALL.
